(57) **CLAIM**

The ornamental design for the dual wall composting bin, as shown and described.

DESCRIPTION

FIG. 1 is a perspective view of the dual wall composting bin showing my new design;

FIG. 2 is a side elevational view thereof;

FIG. 3 is a top elevational view thereof; and,

FIG. 4 is a bottom elevational view thereof.

The broken lines shown in the drawings are included for the purpose of illustrating portions of the dual wall composting bin which form no part of the claimed design.
